Application November 29, 1954, Serial No. 471,660

6 Claims. (Cl. 315—3.5)

The present invention relates to traveling-wave tubes having improved unidirectional attenuation characteristics, and more particularly to a traveling-wave tube including apparatus utilizing the characteristics of ferrite materials capable of attenuating the energy of a wave propagated in one direction by the wave propagating structure without substantially affecting the energy of waves propagated in the opposite direction.

The traveling-wave tube of the present invention incorporates a slow-wave propagating structure of the type disclosed in a copending application for patent Serial No. 450,987 entitled, "High Power Microwave Tube" filed on August 19, 1954, by Charles K. Birdsall. This slow-wave structure comprises a series of periodically spaced conductive rings of uniform diameter alternately connected together with longitudinal conductors at diametrically opposite points on the rings. An analysis of the wave propagating characteristics of this structure shows that the portions of the wave contiguous to the structure and in quadrature with the longitudinal conductors are substantially circularly polarized whereas the portions of the wave along the longitudinal conductors are linearly polarized.

In accordance with the present invention, ferrite members are disposed contiguously along the above wave propagating structure only in the region where the propagated wave is substantially circularly polarized. A magnetic field is produced through each ferrite member in a direction to effect unidirectional attenuation of an electromagnetic wave propagated by the structure. That is, the ferrite material has little or no effect on a wave propagated in a forward direction but attenuates a wave propagated in a backward direction. The absence of ferrite material along the longitudinal conductors minimizes attenuation of the forward wave thereby greatly enhancing the utility of the device. In accordance with an alternate embodiment of the invention a plurality of air gaps is interposed longitudinally along the ferrite members to increase their reluctance to the magnetic field generally employed to focus or constrain the electron stream. Also, in another embodiment of the invention, the ferrite members are divided into predetermined lengths along the longitudinal axis of the propagating structure and different magnetomotive forces are developed across the different lengths of ferrite so as to attenuate a wave propagated in a backward direction over a broad range of frequencies.

At the present time it has been proposed to provide a unidirectional slow-wave propagating structure by disposing a ferrite helix contiguously about a conventional conductive helix. The higher relative permeability of the ferrite material causes a portion of the longitudinal magnetic field normally employed to focus the electron stream to be shunted through the ferrite helix. A portion of the magnetic field is thus directed circumferentially around the conductive helix thereby effectuating unidirectional attenuating characteristics in the ferrite material. It has been found that a device of this type has

2

limitations in that the complex configuration of the ceramic ferrite material makes fabrication difficult and, in addition, the magnetomotive force necessary to operate the ferrite at gyroresonance for the higher microwave frequencies, i. e. the degree of saturation necessary to produce unidirectional attenuation, is normally substantially more than that necessary for focusing the electron stream.

It is therefore an object of the present invention to provide a traveling-wave tube incorporating an improved slow-wave propagating structure having unidirectional attenuating characteristics.

Another object of the present invention is to provide a traveling-wave tube incorporating apparatus including ferrite members of simple configuration capable of attenuating an electromagnetic wave propagated by a contrawound helix in a backward direction without substantially affecting a wave propagated in the forward direction.

Still another object of the present invention is to provide a traveling-wave tube incorporating a contrawound helix together with apparatus capable of dissipating energy propagated by the helix in one direction over a wide range of frequencies without substantially affecting wave energy propagated in an opposite direction by the helix.

The novel features which are believed to be characteristic of the invention, both as to its organization and method of operation, together with further objects and advantages thereof, will be better understood from the following description considered in connection with the accompanying drawings in which several embodiments of the invention are illustrated by way of example. It is to be expressly understood, however, that the drawings are for the purpose of illustration and description only, and are not intended as a definition of the limits of the invention.

Fig. 1 is a diagrammatic sectional view of the tube of the invention together with associated circuitry;

Fig. 2 is a cross sectional view taken on line 2—2 of Fig. 1;

Fig. 3 is a schematic diagram of the current flow along the contrawound helix included in the tube shown in Fig. 1;

Fig. 4 is a cross sectional view taken on line 4—4 of Fig. 1 of the contrawound helix shown in Fig. 1 showing the magnetic field configuration for the current flow of Fig. 3;

Figs. 5 and 6 show vectors illustrating the circular polarization characteristics of the wave propagated by the contrawound helix shown in Fig. 4;

Fig. 7 is a graph showing a typical permeability characteristic for a ferrite material in the gyroresonance region;

Fig. 8 is a graph illustrating the relative unidirectional attenuating characteristics of the device of Fig. 1;

Figs. 9 and 10 show modifications of the unidirectional attenuating apparatus of the device of Fig. 1; and

Fig. 11 is a graph showing a representative broad band unidirectional attenuation characteristic capable of being effectuated by the modification shown in Fig. 10.

Referring now to Fig. 1, there is shown a diagrammatic sectional view of an embodiment of the traveling-wave tube of the present invention. An envelope 10, which provides the necessary evacuated chamber, comprises an elongated portion 11 with an enlarged portion 12 at its left extremity as viewed in the drawing. Within the enlarged portion 12 there is disposed an electron gun 14 capable of producing a hollow cylindrical electron stream. Electron gun 14 includes an annular cathode 16 with a heater 18, a focusing electrode 20, and an accelerating anode 22, the electrodes 20 and 22 being provided with apertures in register with the electron emitting annular

surface of cathode 16 to allow passage therethrough of the electron stream.

The electron emitting surface of cathode 16 is disposed concentrically about and in a plane normal to the longitudinal axis of envelope 10. Its heater 18 is energized by a connection across a source of potential, such as a battery 24. The focusing electrode 20 provides an inner and an outer surface of revolution disposed adjacent to and at an angle of approximately 67.5° with the electron emitting surface of cathode 16, as shown in the figure, to provide for focusing the electron stream. Cathode 16 and focusing electrode 20 are connected together and are, in turn, connected to the negative terminal of a battery 26, the positive terminal of which is connected to ground. The magnitude of the potential provided by battery 26 may be of the order of 3000 volts. Accelerating anode 22 is disposed in a plane normal to the longitudinal axis of envelope 10 and to the right of focusing electrode 20 as viewed in the drawing. Anode 22 is maintained at a substantially fixed potential that is of the order of 300 volts positive with respect to ground by means of a connection to the positive terminal of a battery 28, the negative terminal of which is connected to ground.

A solenoid 30 is disposed concentrically about the complete length of the elongated portion 11 of envelope 10. An appropriate direct current is made to flow through the solenoid 30 by means of a connection across a battery 32 so as to produce a magnetic field of the order of 600 gauss extending longitudinally along the tube. The purpose of this magnetic field is to focus or constrain the electron stream along a predetermined path that is coextensive with the active length of the tube.

A collector electrode 34 is disposed at the extremity of this path farthest from the electron gun 14 to intercept and collect the electron stream. Collector electrode 34 is maintained at a potential of the order of 200 volts positive with respect to ground by means of a connection thereto to the positive terminal of a battery 36, the negative terminal of which is connected to ground.

Disposed concentrically around and contiguously along the path of the electron stream and extending from the electron gun 14 to the collector electrode 34 is a contrawound helix 40 comprising ferrules 41, 42 at its extremities and a plurality of annular rings 44 of equal diameter spaced periodically therebetween and connected together at diametrically opposite points by longitudinal conductive members 46. Helix 40 is preferably fabricated from a single nonmagnetic tubular piece of metal such as, for example, tungsten or molybdenum.

An equipotential region between the electron gun 14 and the helix 40 is provided by a conductive coating 48 disposed therebetween on the inner surface of envelope 10. Conductive coating 48 may be provided, for example, by a colloidal suspension of graphite in water known commercially as "aquadag." Both helix 40 and conductive coating 48 are maintained at ground potential by suitable connections to ground.

Contrawound helix 40 is energized with an electromagnetic signal to be amplified by means of an input wave guide section 50 which symmetrically encloses the elongated portion 11 of envelope 10 coextensive with the longitudinal conductive member 46' of helix 40 nearest the electron gun 14. Input waveguide section 50 is terminated so as to produce a voltage maximum at a point coinciding with the longitudinal conductive member 46' and, in addition, has a sleeve 51 extending contiguously along the envelope 10 for a distance necessary to produce a virtual shorting plane at the inner surface of waveguide section 50 nearest the electron gun 14. Similarly, an output from the tube is provided by an output wave guide section 52 which symmetrically encloses elongated portion 11 of envelope 10 coextensive with the longitudinal conductive member 46" farthest along the path of the electron stream. Waveguide section 52 is terminated so as to optimize the energy transfer thereto

from the contrawound helix 40. Also, a sleeve 54 extends contiguously along envelope 10 along ferrule 40 for a distance necessary to produce a virtual shorting plane on the inner surface of the waveguide farthest from electron gun 14 in the same manner as on waveguide section 50.

Disposed along the outer circumference of contrawound helix 40 in quadrature with the longitudinal conductive members 46, 46', 46" are ferrite slabs 60 and 62 composed of, for example, ferrite material known commercially as "Ferramic A," "Ferramic G," "Ferramic R-1," "Ferroxcube 104" or "Ferroxcube 106." These slabs are shown in partial section in Fig. 1 and in cross section in Fig. 2. Referring to Fig. 2, the height of the ferrite slabs 60, 62 is of the same order of magnitude as the contrawound helix 40. Ferrite slabs 60 and 62 are of the order of 0.014 inch thick and spaced 0.020 inch from the outer periphery of the helix 40. As shown in the present embodiment, the ferrite slabs 60, 62 are disposed inside the evacuated envelope 10. In this event, it may be necessary to seal the exterior of the ferrite members with a thin layer of material such as, for example, glass in order to maintain a suitable vacuum within the envelope 10. A method and apparatus for accomplishing this is disclosed in a copending application for patent Serial No. 430,841 entitled, "Vitreous Coated Magnetic Material" filed on July 19, 1954, by Arthur H. Iversen. Alternatively, it is apparent that the ferrite slabs 60, 62 may be located outside of the evacuated chamber provided by envelope 10.

In accordance with the present invention, transverse magnetic fields of opposite directions are produced through slabs 60 and 62. To accomplish this an iron core 64 having a length that is coextensive with that of ferrite slabs 60, 62 is provided. This core is disposed on top of the elongated portion 11 and has pole pieces positioned in register with the edges of the ferrite slabs 60, 62. Iron core 64 is laminated in a direction transverse to the longitudinal axis of envelope 10 so as to present a high reluctance path to the magnetic field used for focusing the electron stream. In order to complete the magnetic path through ferrite slabs 60, 62, an iron core 66, similar to the iron core 64, is disposed across the opposite edges thereof. A solenoid 68 is disposed about the core 64 and connected across a variable voltage source 70. Source 70 is adjusted so that there are sufficient ampere-turns about the core 64 to develop a magnetomotive across each of the ferrite slabs 60 and 62 of the order of 1500 oersteds, depending on the frequency and type of ferrite used.

During the operation of the device of the present invention, an electromagnetic wave is propagated by the contrawound helix 40. As in any propagating structure, in order to cause currents to flow it is necessary to provide a boundary for an electrodynamic field. Referring now to Fig. 3 there is shown a sectional schematic diagram of contrawound helix 40 with arrow indicating the instantaneous current flow thereon for an electromagnetic wave propagated in the "forward" direction along the path of the electron stream. As shown in this diagram, the current flow divides and flows in parallel about each half of the annular rings 44 and combines when flowing along the longitudinal conductive members 46. This current flow generates the magnetic field portion of the electromagnetic wave propagated by the contrawound helix 40.

To illustrate more clearly the magnetic field portion of the waves nearest the ferrite slabs 60, 62 reference is made to Fig. 4, which shows section 4-4 of Fig. 1. This is a cross section view of the ferrite slabs 60, 62 and contrawound helix 40 taken in a horizontal plane, as viewed in the drawing, that passes through the points of helix 40 nearest the ferrite slabs. In this figure, the instantaneous magnetic field for a current flow indicated in Fig. 3 is shown by dash lines 70 for the side nearest ferrite slab 60 and dash lines 72 for the side nearest ferrite slab

62. In the operation of the tube of the present invention, magnetic fields of this type are propagated along the path of the electron stream by the contrawound helix 40 at a velocity designated as the phase velocity of the wave.

In order to consider the characteristics of the magnetic field represented by dash lines 70, the field will be viewed from a single point within the ferrite slab 60 such as, for example, at point A. It is seen that the magnetic field for the particular instant shown may be represented by vector $\bar{a}$ as illustrated in Fig. 5. As the wave progresses along the helix 40, point A will be successively cut by other points of the magnetic field where the magnetic field may be represented, respectively, by vectors $\bar{b}$, $\bar{c}$ and $\bar{d}$. Thus, as viewed from point A, it is seen that the magnetic field may be represented by a vector that rotates in a counter-clockwise direction at an angular velocity ω_1 . When the moment of this rotating vector coincides with the direct-current magnetic field through the ferrite slab 60, the component of the wave described is said to be positive circularly polarized. Alternatively, if the moment of the rotating vector is in an opposite direction, the particular component described would be negative circularly polarized. Similarly, point B within slab 62 sees successive magnetic vectors $\bar{e}$, $\bar{f}$, $\bar{g}$ and $\bar{h}$ illustrated in Fig. 6. As before, these vectors may be represented as a single vector rotating in the counter-clockwise direction at an angular velocity ω_2 .

In accordance with the present invention, the magnetic field through ferrite slabs 60, 62 is directed in a manner such that the magnetic field components of the wave being propagated in the forward direction will be negative circularly polarized. In that the magnetic field intercepting both ferrite slabs 60, 62 rotates in opposite directions, it is apparent that in order to have components of the propagated wave on both sides of helix 40 polarized in the same direction, it is necessary that the direct current magnetic field through ferrite slab 62 be in a direction opposite to that through slab 60.

As is generally known, the permeability characteristics for positive and negative circularly polarized waves of ferrite material are different. More particularly, the permeability for the negative circularly polarized wave is substantially constant, whereas the permeability for the positive circularly polarized wave goes through resonance for changes in frequency or magnetic field. During resonance the power dissipated in the material increases substantially, thereby making the permeability for a positive circularly polarized wave a complex quantity. A typical permeability characteristic for a ferrite material is shown in Fig. 7 wherein μ_- represents the permeability for the negative circularly polarized wave and $\mu_+ = \mu' - j\mu''$ represents the permeability for a positive circularly polarized wave. As illustrated in this figure, lines 80, 82 and 84 represent the variation in μ_- , μ' and μ'' , respectively, versus frequency for circularly polarized waves. The magnitude of μ'' , i. e. the imaginary part of μ_+ , determines the extent to which the positive circularly polarized wave will be attenuated. As shown in the figure, maximum attenuation of the positive circularly polarized wave occurs at the resonant frequency. The point at which this resonance occurs is both a function of the frequency of the circularly polarized wave as seen by the ferrite material and the strength of the direct current magnetic field across the ferrite.

Thus, in the operation of the device of the present invention, the current through solenoid 68 which determines the direct current magnetic field is adjusted by means of variable potential source 70 to produce a magnetic field within the ferrite material corresponding to resonance at the operating frequency.

In operation of the device of the present invention, the function of the ferrite slabs 60, 62 is to attenuate electromagnetic wave energy being propagated by the contrawound helix 40 in the direction from the collector 34 to

electron gun 14, i. e. in the "backward" direction, without appreciably attenuating waves being propagated in the forward direction. The relative attenuation characteristics for a forward and a backward wave for the device of the present invention are shown in Fig. 8 as lines 90 and 92, respectively. The attenuation of a backward wave in decibels is approximately ten times that of a forward wave. On the other hand, if similarly magnetized ferrite slabs were to be disposed contiguously along the longitudinal members 46 of contrawound helix 40, the relative attenuation in decibels of a forward wave would be approximately one-half that of a backward wave. In this case the relative attenuation of a forward wave is represented by dashed lines 94 in Fig. 8. Thus it is apparent that if the ferrite slabs were to be disposed along the longitudinal members 46 of helix 40, the utility of the device of the present invention would be destroyed.

As shown in Fig. 9, an alternative embodiment of the present invention employs a plurality of ferrite slabs 96 in lieu of either one or both of the ferrite slabs 60, 62 shown in Fig. 1. The ferrite slabs 96 are disposed at uniformly spaced intervals, as shown in Fig. 9, and are separated by either air gaps or other low dielectric-constant nonmagnetic material so as to offer a high reluctance path to the longitudinal magnetic field produced by a solenoid 30 to focus the electron stream. The higher reluctance path presented to the longitudinal magnetic field by ferrite slabs 96 minimizes distortion of the transverse magnetic field therethrough produced by solenoid 68 and thus improves the unidirectional attenuation characteristic of the tube.

In another embodiment of the present invention, attenuation of the backward wave over an extended range of frequencies is achieved. As previously mentioned, attenuation of the positive circularly polarized components occurs at a resonant frequency. The exact frequency at which this resonance occurs for a given ferrite material is determined by the direct current magnetic field through the ferrite. The attenuation at each resonant frequency, however, is not necessarily the same. Accordingly, referring to Fig. 10 ferrite slabs 98 are employed in lieu of either one or both of the slabs 60, 62 in the device of Fig. 1. Ferrite slabs 98 comprise, for example, sections 100, 101 and 102. In accordance with the invention, different magnetomotive forces H_1 , H_2 and H_3 are developed, for example, across the sections 100, 101 and 102, respectively, so that maximum attenuation for the sections occur at frequencies f_1 , f_2 and f_3 as shown in Fig. 10. These magnetic fields may be produced, for example, by means of solenoids 103, 104 and 105, respectively. The length of each of the sections 100, 101 and 102 is adjusted so that the attenuation at each of the above frequencies represented by lines 106, 107 and 108, respectively, is the same. Further, the magnetomotive forces H_1 , H_2 and H_3 are chosen to cause the resonant frequencies f_1 , f_2 and f_3 to occur at appropriate intervals so that the composite attenuation represented by dashed line 109 of the sections 100, 101 and 102 is substantially constant within the frequency range from f_1 to f_3 . It is apparent that this also may be accomplished by using different ferrites with substantially equal magnetomotive forces. Under normal circumstances, it is desirable to have the frequency range f_1 to f_3 coextensive with the gain characteristic of the tube so as to prevent self-oscillations at frequencies where the tube still provides substantial gain but has a poor impedance match to its output circuit.

What is claimed is:

1. A traveling-wave amplifier tube comprising means for producing an electron stream; a contrawound helix disposed concentrically about and contiguously along a predetermined path for propagating an electromagnetic signal wave therealong in a forward direction, said contrawound helix including a plurality of equal-diameter conductive annular rings disposed periodically along

said path, and a longitudinal conductive member disposed between each adjacent pair of rings, said longitudinal conductive members interconnecting alternate pairs of corresponding diametrically opposite points on the circumference of each of said rings; means for directing said electron stream along said predetermined path in said forward direction, thereby to amplify said electromagnetic signal wave; output means coupled to said helix, whereby a portion of the energy of said amplified electromagnetic signal wave is reflected and propagated back along said predetermined path in a backward direction; a member composed of ferrite material having a surface disposed contiguously along said contrawound helix in quadrature with the longitudinal conductive members thereof; and means for producing a magnetic field transverse to the longitudinal axis of said helix through said member composed of ferrite material, said magnetic field having an intensity to produce resonance in the permeability characteristic of said ferrite material at the frequency of said wave, thereby dissipating the portion of the energy of said electromagnetic signal wave being propagated along said predetermined path in said backward direction without substantially affecting the magnitude of said wave being propagated along said path in said forward direction.

2. A traveling-wave amplifier tube comprising means for producing an electron stream; a contrawound helix disposed concentrically about and contiguously along a predetermined path for propagating electromagnetic waves therealong in a forward direction, said contrawound helix including a plurality of equal-diameter conductive annular rings disposed periodically along said path, and a longitudinal conductive member disposed between each adjacent pair of rings, said longitudinal conductive members interconnecting alternate pairs of corresponding diametrically opposite points on the circumference of each of said rings; means for directing said electron stream along said predetermined path in said forward direction, thereby to transfer energy from said electron stream to said electromagnetic waves; output means coupled to said helix, whereby a portion of the energy of said electromagnetic waves is reflected and propagated back along said predetermined path in a backward direction; a segment composed of ferrite material having a surface disposed adjacent said contrawound helix in quadrature with the longitudinal conductive members thereof; and means for producing a magnetic field transverse to the longitudinal axis of said helix through said segment composed of ferrite material, said magnetic field having an intensity to cause said ferrite material to dissipate the energy of said electromagnetic waves propagated along said predetermined path in a backward direction without substantially affecting the magnitude of said electromagnetic waves being propagated along said path in a forward direction.

3. The traveling-wave amplifier tube as defined in claim 2 including a plurality of said segments composed of ferrite material, said segments being disposed at intervals along said contrawound helix to increase the reluctance presented to a magnetic field along the longitudinal axis of said contrawound helix.

4. A traveling-wave amplifier tube comprising means for producing an electron stream; a contrawound helix disposed concentrically about and contiguously along a predetermined path for propagating electromagnetic waves therealong in a forward direction, said contrawound helix including a plurality of equal-diameter conductive annular rings disposed periodically along said path, and a longitudinal conductive member disposed between each adjacent pair of rings, said longitudinal

conductive members interconnecting alternate pairs of corresponding diametrically opposite points on the circumference of each of said rings; means for directing said electron stream along said predetermined path in said forward direction, thereby to transfer energy from said electron stream to said electromagnetic waves; output means coupled to said helix, whereby a portion of the energy of said electromagnetic waves is reflected and propagated back along said predetermined path in a backward direction; a plurality of segments composed of ferrite material having surfaces disposed contiguous along said contrawound helix in quadrature with the longitudinal conductive members thereof; and means for producing magnetic fields transverse to the longitudinal axis of said helix and of different predetermined intensities through each of said segments thereby to dissipate energy of said electromagnetic waves propagated along said predetermined path in a backward direction over a broad range of frequencies without substantially affecting the magnitude of said electromagnetic waves being propagated along said path in a forward direction.

5. The traveling-wave amplifier tube as defined in claim 4 wherein the surfaces of said plurality of segments composed of ferrite material disposed contiguously along said contrawound helix are each of predetermined length to produce uniform dissipation of energy throughout said broad range of frequencies.

6. A traveling-wave amplifier tube comprising means for producing an electron stream; a contrawound helix disposed concentrically about and contiguously along a predetermined path for propagating an electromagnetic signal wave therealong in a forward direction, said contrawound helix including a plurality of equal-diameter conductive annular rings disposed periodically along said path, and a longitudinal conductive member disposed between each adjacent pair of rings, said longitudinal conductive members interconnecting alternate pairs of corresponding diametrically opposite points on the circumference of each of said rings; means for directing said electron stream along said predetermined path in said forward direction, thereby to amplify said electromagnetic signal wave; output means coupled to said helix, whereby a portion of the energy of said amplified electromagnetic signal wave is reflected and propagated back along said predetermined path in a backward direction; first and second members composed of ferrite material, said first and second members having surfaces disposed contiguously along both sides of the contrawound helix in quadrature with the longitudinal conductive members thereof; and means for producing magnetic fields in opposite directions through said first and second members and transverse to the longitudinal axis of said helix, said magnetic fields having an intensity to produce resonance in the permeability characteristic of said ferrite material at the frequency of said wave, thereby dissipating the portion of the energy of said electromagnetic signal wave being propagated along said predetermined path in said backward direction without substantially affecting the magnitude of said wave being propagated along said path in said forward direction.
